UNITED STATES PATENT OFFICE.

CARL WINKLER, OF BERNE, SWITZERLAND.

SHEET-FEEDING.

Specification of Letters Patent. Patented Apr. 26, 1921.

1,376,183.

Application filed January 20, 1921. Serial No. 438,803.

To all whom it may concern:

Be it known that I, CARL WINKLER, a citizen of the Swiss Republic, residing at Berne, in the Swiss Republic, have invented a new and useful Sheet-Feeding, of which the following is a specification.

My invention relates to a device for lifting single sheets of paper, or the like, from a pile by suction and blowing. From existing devices of this kind my invention differs by the fact that the blowing nozzles are divided into two different groups with special air tubes. One of these groups of blowers has vertically extending nozzles and such a connection with the pressure pipe that said blowers serve simultaneously to loosen the upper sheets of the pile, and to lift their front edges toward the suction nozzles. As soon as these suction nozzles have seized the top sheet of the pile, the second group of blowers, which has horizontally extending nozzles, enters into action and separates the sheets from the pile in known manner.

By this device the top sheet of the pile can be lifted from the pile with certainty, while the amount of compressed air required is only small, owing to the operations of the two groups of blowers being separate, and the relatively short duration of the separate impulses.

In the drawing illustrating my invention.

Figure 1 is a side elevation of the pile and of the suction and blowing nozzles,

Fig. 2, a back elevation of both groups of blowers,

Figs. 3, 4 and 5 show the valve for regulating the introduction of air to the suction and blowing nozzles in section, side elevation and plan,

Fig. 6 represents the parts for actuating the valves in horizontal section.

The suction nozzles *a* (Fig. 1) are so oscillated about the shaft *b* by the eccentric *c* that the top sheet taken up from the pile *d* is transported farther. For the purpose of better raising the top sheet toward the suction nozzles *a* the blowing nozzles *e* (Fig. 2) have a T-shaped section, and these nozzles are connected with the air-pipe *f*.

When the sheet has been seized by the suction nozzles *a* the connection of the nozzles *e* with the air pressure pipe *f* is cut off, and the nozzles *g* of horizontally extended section begin blowing air under the sheet

raised by the suction nozzles, so that this sheet is completely separated from the pile.

The passage of the compressed air to the nozzles *e* and *g* is controlled by the three-way cock *h*, the casing of which is made in one piece with that of the three-way cock *i*, by which the suction of the nozzles *a* is controlled. The compressed air is fed to the valve casing through the socket *k* from any desired source and passes upward through the valve *l* to the pipe *f* leading to the nozzles *e* by which the pile is loosened or downward through the valve *m* to the pipe *n* leading to the blowers *g* which serve to separate the top sheet from the pile. The valve *l* is fastened to the spindle *o*, while the valve *m* is loosely mounted on said spindle and is pressed down by the spring *p*. By means of the lever *q*, roller *r* and cam disk *s* the valves *l* and *m* are alternately opened and closed.

The valve casing *i* for suction has also two valves. To this casing is connected the suction pipe at *t*, so that when the valve *u* is raised, the suction extends to the nozzles *a*. If the valve *u* is closed, and the lower valve *v* is opened, the suction nozzles are connected with the atmosphere, so that they let loose the sheet which they have advanced somewhat by their swinging motion. These valves *u* and *v* are actuated by the valve spindle *w*, lever *x*, roller *y* and cam disk *z*.

What I claim and desire to secure by Letters Patent of the United States is:—

1. In a device for lifting separate sheets from a pile by means of suction and blowing nozzles, a suction nozzle, a group of vertically extending blowing nozzles for loosening the upper sheet and raising the front edge of the same to the suction nozzle, a second group of horizontally extending blowing nozzles for separating the sheet seized by the suction nozzle from the pile, and means for controlling the blowing nozzles whereby when the last named group are in action the first named group are inactive.

2. In a device for lifting separate sheets from a pile of the kind set forth in claim 1, the use of double valves for controlling the suction and blowing nozzles respectively, one of which valves (*l* or *u*), by which communication is effected between the pressure pipe and one of the groups of blowers (*e*) or between the suction pipe and the suction

nozzles (a), being fastened on the valve spindle (o or w), while the other valve (m or v), by which communication is effected between the pressure pipe and the other group of blowers or between the atmosphere and suction nozzles (a), is adapted to slide on, and is actuated by a sleeve surrounding, said spindle.

3. In a device for lifting separate sheets from a pile of the kind set forth in claim 1, the arrangement of the double valves for

controlling the passage of air to and from the suction and blowing valves in one casting, substantially as set forth.

In testimony whereof I have signed my name to this specification in the presence of two subscribing witnesses.

C. WINKLER.
